United States Patent Office.

THEODORE BEARDSLEY, OF SPRINGFIELD, ASSIGNOR TO HIMSELF AND
J. DANA WYMAN, OF FITCHBURG, MASSACHUSETTS.

Letters Patent No. 74,881, dated February 25, 1868.

IMPROVEMENT IN SOLDERING-IRON.

The Schedule referred to in these Letters Patent and making part of the same.

TO ALL WHOM IT MAY CONCERN:

Be it known that I, THEODORE BEARDSLEY, of Springfield, Hampden county, Commonwealth of Massachusetts, have invented a new and useful Improved "Soldering-Iron;" and I do hereby declare that the following is a full and exact description thereof, reference being had to the accompanying drawings, and to the letters of reference marked thereon. In the drawings—

Figure 1 is a side sectional view of one half of the iron, and

Figure 2 a similar view of the other half.

The object of this invention is to obtain a soldering-iron which shall contain the heating-apparatus within itself, and thus make the tool far more convenient, doing away with the heavy and awkward furnace now in use.

To accomplish this, I form my device as I will now describe.

In the handle, which is hollow, is a reservoir of oil, or other suitable burning-fluid, from which a wick extends through the hollow rod to the iron where the burner is placed, so as to heat the iron in the most thorough manner.

In the drawings, fig. 1 shows the interior of the handle having the oil. In this it is seen that a hollow rod, A, connects the front end of the handle B with the rear end of the small furnace around the iron point C, the rod being represented as broken off in fig. 1, and continued in fig. 2. Extending back from the iron point C is a cylindrical case, D, perforated with a suitable number of holes, *a a*, to allow the free circulation of air. In the centre of this is the burner E, upon the continued end of the hollow rod or tube A, which has attached upon it, just behind the burner, a cylindrical piece, F, connected with the rod by means of small connecting-rods *b b*, &c., shown by dotted lines. This allows the air to circulate freely around the tube A, and to enter the case D at the rear end. The case D fits closely over the cylinder F, at its rear end, the cylinder F having a projection, *e*, upon its circumference, which enters a slot cut into the end of the case D, and prevents the latter from turning.

In order to form a regulating-device for the intensity of the flame at the burner, I place in the handle, extending through from the rear end of the same, through the hollow tube A, to the burner, a rod G, having at its front end a conical cap, H, which fits, when drawn in, into a conical seat formed in the end of the burner. By closing or opening the valve so formed, a graduation of the flame can be effected, and the same entirely extinguished if desired. The device for operating this rod consists in an adjusting-nut, I, at the rear end of the handle. This works upon the threads upon the end of the rod G, so as to push out or draw in the latter. A square socket, *e*, in the end of the cap K, upon the end of the handle, prevents the rod G from turning when the nut I is operating upon it, the latter being formed so that it may turn, but have no lateral motion.

The cap K is screwed upon the rear end of the handle, and is packed with cork, or other suitable material. This cap is taken off when it is desired to fill the reservoir with oil.

The nick L is generally cylindrical, so that the part in the tube A may surround the rod G.

By this arrangement I obtain a soldering-iron which can be kept at any desired heat, containing all the heating-device within itself, making it a convenient tool to be carried about, and dispensing entirely with the furnace usually used for the purpose of heating the irons.

I am aware of the patent of A. N. Burbank for improvement in heating soldering-irons, February 11, 1860, but I do not claim the means used by him.

Now, having described my invention, what I claim as new, and desire to secure by Letters Patent is—

1. A soldering-iron, in which the point is heated by a flame fed by a reservoir of fluid contained in the handle of the instrument.

2. The combination of the valve H, reservoir B, and head C, substantially as and for the purpose set forth.

THEODORE BEARDSLEY.
